UNITED STATES PATENT OFFICE

2,373,436

FASTENER SETTING OR ATTACHING MACHINE

Jacob P. Treciokas, Oakville, Conn., assignor to
Scovill Manufacturing Company, Waterbury,
Conn., a corporation of Connecticut

Application March 18, 1943, Serial No. 479,563

8 Claims. (Cl. 218—6)

This invention relates to improvements in fastener-setting or attaching machines adapted for use in securing together parts of buttons or fastener elements upon a supporting structure such as garments or other articles of fabric material. As herein disclosed the fastener elements may consist of an eyelet member and a hollow button member within which the shank end of the eyelet member may be upset when attaching the fastener members to their support.

The machine in general comprises an anvil upon which the eyelet member may be positioned with the shank projecting upwardly, a pair of jaws by which the button member may be positioned over the eyelet shank, and a setting tool in the form of a plunger by which the button may be released from the jaws and the button and eyelet secured together by relative movement between the tool and anvil.

Heretofore, it has been the more common practice in machines of the above nature to feed the fastener element, which in this case is the button member, to the upper jaws through feed tracks from a hopper depending entirely upon the force of gravity. In practice in conventional machines in resorting to gravity as a feeding means, where the operator is working upon a garment or some device to which fasteners are to be set relatively close together, it has been found that the operator can work faster than the speed in which the fasteners could be fed into the jaws by gravity, and, therefore, resulted quite frequently in a missing fastener or in a deformed fastener. This has been particularly true in machines that are either foot-operated such as disclosed in the Veillette Patent No. 1,836,887, or operated by a crank connection connected to a clutch operated drive shaft, such as disclosed in the Warner Patent No. 1,575,596.

In order to overcome the above faults there is incorporated in the above type of fastener machines a positive means for feeding the button elements into the upper jaws of the machine directly from the end of a raceway. With this change in the feeding mechanism associated with the upper jaws it became necessary to provide a means for assuring that the jaws will be brought to button receiving position at the proper time to receive the button element from the positive feeding element means. It is, therefore, one of the objects of this invention to provide a mechanism that is operated from the setting plunger operating means for imparting return motion to the jaws to attain the proper return timing rela-

tionship of the jaws to the element feeding mechanism.

Further objects and advantages of this invention will appear more fully from the following description particularly when taken in connection with the accompanying drawings illustrating the preferred form of the invention wherein:

Fig. 1 is a side view of a portion of the machine embodying the improvements, parts of which are broken away to show better the structural details, with the upper jaws and setting punch shown in retracted position and the means for feeding the fastener elements into the upper jaws in partially retracted position.

Fig. 2 is a front elevational view of the portion of the machine shown in Fig. 1.

Fig. 3 is a fragmentary view similar to Fig. 2 but showing the upper jaws and associated mechanisms in an advanced position such as they assume during the fastener setting operation.

Fig. 4 is a side elevational view of Fig. 3.

Fig. 5 is a fragmentary view of the upper jaw feeding means and showing a button element in the process of being picked up from its track and fed into the jaws.

Fig. 6 is a similar view showing the feeding means having advanced the button completely into its receptive socket in the jaws, and

Fig. 7 is an enlarged sectional view taken transversely at the end of the button feed track on line 7—7 of Fig. 1 but after retraction of the feed finger.

The invention to be described is applied to a portion of the machine comprising a bearing block 10 supported by a head 11 extending upwardly and forwardly from a portion of the machine bed plate 12 which in turn may be mounted upon a suitable pedestal or support 13, a portion of which is shown in Fig. 2. Mounted upon the bed plate 12 is an anvil 14 for the purpose of receiving a fastener element herein described as an attaching eyelet 15.

As a means for properly positioning and retaining the attaching eyelet or fastener element 15 upon the anvil 14 a pair of lower jaws 16 may be provided between which the eyelet may be thrust prior to a setting operation. These jaws 16 may be pivotally connected as at 17 to a vertical movable slide 18 connected by means of a link 19 with the forward end of a lever 20, which is adapted to be pivoted in an embossed portion 13a of the pedestal 13 and actuated by suitable mechanism to move the link 19 downwardly and cause the lower jaws to spread so as to remove them from the fastener element during

the setting operation. The jaws may be yieldingly held in their normal fastener receiving position by a spring 21.

The attaching eyelets 15 are fed from a hopper (not shown) and stacked in a raceway 22 leading to a guideway 23, and prior to each setting operation a single eyelet is picked up from the end of the raceway 22 and thrust forwardly through the guideway 23 as by means of a feed slide 24 to its proper position upon the anvil 14. The feed slide 24 in turn is actuated by a link 25 operated from any suitable mechanism of the machine.

In order to supply a complementary fastener element for the attaching eyelet 15, such as a button member 26, and carry it into alignment therewith for the purpose of attaching the same upon a supporting member, means is provided in the form of a plunger 27 mounted in the bearing block 10 and adapted to move longitudinally with its axis in alignment with the anvil 14. To provide for the endwise movement of the plunger 27, it is connected by means of a link 28 to the forked end of a main lever 29 through a connecting pin 30. The lever 29 is pivoted as at 31 to the head 11. The lower end of the plunger 27 is provided with a setting tool or punch 32 having a reduced portion 32a for fitting into the hollow of the button member and serving to upset the end of the eyelet 15 coincident with the setting operation.

As a convenient means for positioning the button element 26 in alignment with the setting tool 22 a pair of upper jaws 33 are provided and slidably mounted to an integral portion 10a projecting from the front face of the bearing block 10. The lower ends of the jaws 33 are provided with inturned portions 35 that are adapted in normal position to be aligned with a feed track 36 through which the button elements 26 are fed from a suitable hopper (not shown) in a manner as will be more fully explained later. The upper ends of the jaws 33, as best shown in Fig. 2, are hinged together as by a pivot screw 37 in order to allow the lower inturned portions 35 thereof to swing outwardly for releasing the button therefrom and allow the setting tool 32 to pass therethrough coincident with the setting operation, and the jaws are normally held in a clamped closed position by means of a spring 38. The inturned ends 35 of the jaws have their adjacent faces cut out to provide a suitable recess or socket 34 for the reception of the button element 26 when fed therewith from the feed track 36 and also to allow for clearance for the descending setting tool 32 when removing the button from said jaws. The jaws 33 are held in slidable and frictional relation to the face of the block projecting portion 10a as by means of screws 39 and 40 secured thereto, and the adjacent edges of the jaws are cut away to form an intermediate longitudinal slot 41 for clearing the shanks of the screws 39 and 40. The upper screw 39 supports a friction washer 42 that is compressed against the face of the jaws 33 by means of a coil spring 43. The lower screw 40 supports a spreading cam member 44 for the purpose of spreading the jaws 33 manually in case it is desired to remove a fastener from the jaw ends. The jaws and associated attaching parts form no part of the present invention except inasmuch as they cooperate therewith, and are functionally operated with the inventive features of the machine.

As was pointed out in the introductory remarks 75

of this invention, in order to speed up the feed of the button elements into the upper jaws 33 provision is made for positively feeding the buttons directly into said jaws from the feed track 36.

5 As best shown in Figs. 1, 4, 5 and 6, the lower end of the feed track 36 is formed with a rather abrupt bend or arcuate portion 36a that positions the discharge end of the track 36 in a substantially horizontal position and directly in alignment with the inturned jaw ends 35.

10 The feed track 36 is provided with a T-shaped slot or guideway, the central wider portion 49 of which is adapted to accommodate the enlarged head of the button elements, and the narrow portion 50 of which opens through the feed track 36 and is adapted to accommodate the shank of the buttons.

15 The buttons are adapted to slide by gravity from a suitable hopper (not shown) down to the arcuate portion 36a of the track where the foremost button will be stopped by a stop pin 51 and the following buttons will stack up in the T-shaped slot 49, 50. The pin 51 is held normally in a depressed position by means of a leaf spring 52 secured to the upper face of said feed track. The width of the guideway 49 is somewhat greater than the normal thickness of the button head so as to allow the buttons to be readily guided around the twisted portion of the track as is indicated at 36b (Fig. 1) without jamming therein. To prevent the button heads from overlapping each other when they approach the stop pin 51 a restrictive plate 53 is secured to the arcuate portion 36a of the feed track within the upper part 20 of the guideway 49, as shown in Fig. 1.

25 The purpose of the abrupt bend or arcuate portion 36a of the feed track is to cause the button shanks in that part of the track to assume a radially spread position to allow for the flattened portion or feed finger end 54a of a reciprocatory rod 54 to advance in alignment with the narrow recess 50 of the T-slot and engage the shank of the foremost button only and feed the same past the stop pin 51, and thence into the jaw recess 34. In forcing the button past the stop pin 51, the latter will be forced upwardly against the influence of the spring 52. The act of feeding the foremost button past the stop pin 51 is best shown in Fig. 5, and it will also be noted in this figure that the upper surface of the feed finger also serves as a stop for the next succeeding button during the time that it is feeding the foremost button into the jaw ends 35. When the feed finger rod 54 has been retracted to its starting position the next succeeding button will then by gravity be caused to slide into engagement with the stop pin ready to be picked up by the feed finger on the next stroke. The feed finger rod 54 is slidably mounted in a bracket bearing 55 secured to the head 11.

30 In order to provide a safety feature in case the button elements should become stuck or jammed within the jaws 33 or feed track 36 during the feeding operation, the feed finger rod 54 is operated through a cushioned plunger 56. Specifically the plunger 56 is slidably mounted in a suitable recess 57 in head 11 and is provided with a hollow interior 58 into which is received a relatively heavy compression spring 59, one end of which is abutted against the base of the hollow interior and the other end against the adjacent end of the feed finger 54. Outward movement of the feed finger relative to the plunger 56 is prevented by means of a transverse pin 60 secured to the inner end of the feed finger rod 54.

and slidably operated in a pair of opposed longitudinal recesses 61 formed axially in the plunger 56 as shown in the sectional portion of Fig. 1. The plunger is adapted to be reciprocated through a link 62 tied into a suitable operating part of the machine.

Since it is one of the purposes of this machine to feed the fastener buttons into the recesses 34 of the jaws at a speed greater than can be attained by gravity due to the feeding mechanism explained immediately above, in machines that are operated through a foot-lever mechanism or from a crank off from a clutch operated shaft, it is, of course, necessary that the jaws be returned in proper timed relationship relative to the element feeding mechanism to be in position to receive the foremost button from the track 36 into the jaw recesses 34 as said foremost button is force fed into the jaws 33 by the positive action of the feed finger rod 54. It is to be here understood that the manner in which the jaws 33 are carried downwardly is due to the fact that a button element is supported within the jaw recesses 34 by the clamping action of the spring 38, and as the plunger 27 descends the setting tool 32 engages with the clamped button and causes the jaws to be carried down with the plunger 27 until such time that the upper end of the jaw slot 41 contacts the shank of the upper screw 39 as a stop. The plunger 27, however, continues to descend forcing the button from the jaw recesses 34 and carrying it into engagement with the eyelet 15 and interposed supporting sheet, whereupon the jaws will assume the position as shown in Fig. 3, i. e., slightly spread apart due to the fact that the setting tool 32 has been forced therethrough.

In order to provide a means for returning the jaws 33 to proper fastener receiving position to receive the accelerated fed button from the feed finger end 54a, the following mechanism is provided. This mechanism to return the jaws is provided in the form of a linkage means that has a resilient connection with the jaws and is connected to the main lever through an extension member having pivotal connection with the linkage means in advance of the pivotal connection of the plunger with said lever, thus in fact extending the length of the lever and adding to the effective stroke that may be transmitted to the jaws. Specifically this mechanism comprises a pair of abutment pins 63 attached to the opposed side faces of the jaws 33 and having guide-rods 64 slidable therethrough. Coiled compression springs 65 are supported upon the rods 64 below the abutment pins 63 and maintained upon the rods as by means of nuts 66 engaging the lower threaded ends thereof. The nuts allow for suitable adjustment for the springs 65 to increase or decrease their resilient effect as desired. The upper ends of the guide-rods are provided with rod heads 67 to which the lower ends of the connecting rods 68 are secured as by means of pivot screws 69. The upper end of each connecting rod 68 is attached to the embossed end 70a of extension links 70 as by means of a single pin 71 passing through both links and upper ends of connecting rods 68. The extension links 70 are attached to the main lever 29 somewhat in back of the plunger link connecting pin 30 as by means of pivot screws 72.

Operation

In the operation of this machine, during the time that the jaws 33 and plunger 27 are being

returned to normal uppermost position, a fastener element 15 will be fed into the jaws 16 by means of the slide 24 in the usual manner and held in place upon the anvil 14 by the lower jaws 16. The feed finger end 54a of the rod 54 will, after the start of the feeding of element 15 advance to pick up the foremost button in the discharge end of the feed track 36, causing it to snap past the stop pin 51 and into the recesses 34 of the inturned jaw ends 35, and immediately start to retract before the plunger 27 descends far enough to start moving the jaws downward. During the descent of the plunger the setting tool 32 will contact the button element and, due to the clamping action of the jaws 33 upon the button, will force the button downwardly along with the embracing jaws until such time that the upper end of the longitudinal slot 41 of the jaws contacts the upper stationary screw 39, whereupon the jaws will come to a definite stop. The plunger, however, will continue to descend carrying the button with it, causing the jaws 33 to pivot for clearance purposes and then set the button and eyelet upon the intermediate supporting member.

Coincident with the descent of the jaws 33 the guide-rods 64 will move faster than the jaws and slide in the abutment pins 63 due to the expansive force of the coiled springs and the increased stroke permitted thereto from the main lever through the extension links 70. As shown in Fig. 1 the extension links 70 are normally disposed with their lower edges in contact with connecting pin 30 which extends beyond the opposite faces of the forked end of main lever 29 primarily for that purpose. The connecting rods 68 and associated guide rods 64 will travel down until such time as the rod heads 67 of the latter contact the abutment pins 63 fixed to jaws 33, at which time the coil springs 65 will have expended their expansive energy and in fact be spaced somewhat apart from said abutment pins 63, as shown in Fig. 3. With the jaws 33, and therefore rods 64 and 68 in stopped position, pivot point 71 will descend no farther and further movement of the lever 29 will cause pin 30 to move away from links 70 and will cause the links 70 to pivot relative to pivot connections 72 to a position such as is indicated in Fig. 4. Due to the grip of friction washer 42 on jaws 33 the latter will tend to remain in their lowered position so that during the upstroke of the plunger 27 a lost motion results between the plunger 27, jaws 33 and rods 64, wherein the initial movement of the plunger 27 will be independent of the jaws 33 and rods 64, which will remain stationary until such time that the projecting ends of the pin 30 have risen sufficiently to contact the extension links 70, whereupon the connecting rods 68 move the guide rods 64 causing the coiled springs 65 to come in contact with the abutment pins 63, and upon sufficient compression of the coiled springs 65 to overcome the frictional factor of the washer 42 against the jaws 33 the latter will move upwardly concurrently with the guide rod 64 and be returned to starting position, which position is determined by a shoulder 73 on jaws 33 abutting against the lower corner of block extension 10a. Further movement of the guide rods 64 relative to the jaws 33 is permitted by the spring 65 being further compressed and serving to hold the jaw shoulder 73 more rigidly in contact with its abutment 10a an thus assuring alignment of the jaw ends 35 with the bent discharge end 36a of the feed track 36. Upon the

jaws 33 reaching the proper elevation the feed finger end 54a of rod 54 feeds an element 26 into the recess 34 and immediately retracts to permit the descent of plunger 32.

While there has been illustrated and described a machine that has been built and successfully operated embodying the inventive concepts of my invention, it should be understood that the invention is not intended to be limited to the specific form disclosed in this application, but should be regarded as including modifications and variations thereof within the scope of the appended claims.

I claim:

1. In a fastener attaching machine for securing a fastener element to a support comprising, in combination, a bearing block, a plunger movably mounted therein, an operating lever connected to the upper end of said plunger, a pair of separable jaws mounted on said block and movable in the direction parallel with said plunger, means for yieldingly opposing the separation of said jaws, a pair of stops for limiting the movement of the jaws in either direction, said jaws being provided with means for receiving and retaining a fastener element in line with said plunger which in its descent will engage said element and cause said jaws to descend with said plunger until the jaws will engage one stop whereupon said plunger will descend through said jaws forcing the fastener element thereout and cause said jaws to hinge outwardly against the influence of said yielding means, slidable means connected to said jaws, and linkage means connecting said slidable means to said operating lever in advance of the plunger connecting point whereby said linkage means and said slidable means function to impart a greater distance of travel to said jaws relative to said plunger during a portion of the upstroke.

2. In a fastener attaching machine as defined by claim 1 wherein a resilient means is interposed between the jaws and slidable connecting means.

3. In a fastener attaching machine comprising, in combination, a bearing block, a plunger setting tool axially movable therein, a lever operatively connected to the upper end of said plunger, a pair of jaws frictionally mounted upon said block and having opposed recesses for receiving and operating a fastener element in alignment with said plunger setting tool, slidable means having a lost movement connection with said jaws, and linkage means connecting said slidable means to said lever in advance of the point of connection of said plunger setting tool to said lever such that a longitudinal movement imparted to said jaws during a part of their return stroke will be greater than the movement imparted to said plunger setting tool.

4. In a fastener attaching machine comprising, in combination, a bearing block, a plunger setting tool axially movable therein, a lever operatively connected with upper end of said plunger, a pair of jaws frictionally mounted upon said block and having opposed recesses for supporting a fastener element in alignment with said plunger setting tool, means having slideable connection with said jaws, an extension means associated with said lever projecting a substantial distance beyond the point of plunger setting tool connection with said lever, and means connecting said jaw slideable means with the distal end of said lever extension means.

5. A fastener attaching machine as defined by claim 4 wherein the lever extension means has a pivotal connection with said lever.

6. In a fastener attaching machine comprising, in combination, a bearing block, a plunger setting tool axially movable therein, a lever having a link connection with the upper end of said plunger, a pair of jaws frictionally mounted upon said block and having opposed recesses for supporting a fastener element in alignment with said plunger setting tool, a bearing member attaching to said jaws, means slidably mounted in said bearing member, a compression spring compressible between one end of said slideable means and bearing member, an extension means having one end pivoted to said lever in back of said plunger link connection and extending to a point in advance thereof and operating against a stop on said lever, and linkage means connecting said slideable means with said extension means.

7. In a fastener attaching machine as defined by claim 6 wherein adjustable means are provided on said slideable means for varying the force of said compression springs.

8. In a fastener attaching machine comprising, in combination, a bearing block, a plunger axially movable therein, a lever operatively connected with the upper end of said plunger, a pair of jaws frictionally mounted upon said block and operating between predetermined stops, said jaws having opposed recesses for supporting a fastener element in alignment with said plunger, means having slideable connection with said jaws, an extension means having pivotal connection with said lever inwardly of and projecting a substantial distance beyond the point of the plunger connection with said lever, lateral projections on said lever engaged by an intermediate part of said extension means, and means connecting said jaw slideable means with the distal end of said lever extension means.

JACOB P. TRECIOKAS.
